PLAY TENT

Earl C. Wallace, Andrews, and James J. Meekin, Huntington, Ind., assignors to The Hettrick Manufacturing Company, Toledo, Ohio, a corporation of Ohio

Application October 29, 1956, Serial No. 43,550

Term of patent 14 years

(Cl. D34—15)

The dominant features of our new design are shown in solid lines in the drawing.

We claim:

The ornamental design for a play tent, as shown and described.
